UNITED STATES PATENT OFFICE.

FRANK P. WILLIAMS AND ALLAN McINTYRE, OF DETROIT, MICHIGAN.

METAL DESK.

1,397,827.

Specification of Letters Patent.

Patented Nov. 22, 1921.

Application filed November 13, 1920. Serial No. 423,856.

To all whom it may concern:

Be it known that we, FRANK P. WILLIAMS and ALLAN McINTYRE, citizens of the United States, residing at Detroit, in the county of Wayne and State of Michigan, have invented certain new and useful Improvements in Metal Desks, of which the following is a specification.

This invention relates to sheet metal desks, and has for its object a sheet metal desk made up of sheet metal that is folded and seamed together without bolts except in one or two instances. The job may be, therefore, very cheaply manufactured, and the finished desk presents a fire-proof, economical and light desk construction.

In the drawings,—

Figure 1 is a perspective of the desk.

Fig. 2 is a section on the line 2—2 of Fig. 1.

Fig. 3 is a section on the line 3—3 of Fig. 2.

Fig. 4 is a section on the line 4—4 of Fig. 3.

Fig. 5 is a section on the line 5—5 of Fig. 2.

Fig. 6 is a section on the line 6—6 of Fig. 5.

Fig. 7 is a fragmentary perspective of the upper drawer support and guide.

Fig. 8 is a fragmentary perspective of the end of one of the top rails or glass retainers.

Fig. 9 is a section on the line 9—9 of Fig. 1.

Fig. 10 is a perspective of the central tie plate between the two cabinets of drawers.

Fig. 11 is a perspective partly in section showing how the side plate fits into the corner plate.

The desk is made up of a pair of cabinets of drawers connected together, the slab of glass *a* forming the top. Each cabinet or drawer is made up of side walls *b* and *c*, a front wall *d* and rear wall *e*. Each of these

has a lock-seam fold *b*¹, *c*¹, *d*¹ and *e*¹ respectively, turned over at right angles at the top, and a seam fold *b*², *c*², *d*² and *e*², turned over on the inside on the bottom. Into the bottom folds *b*², *c*², *d*² and *e*² locks the right

angular flanges *f* of the bottom plate *g* of the cabinet. There also locks into the folds *b*² and *c*² the right angular flange *h* of the plates *i* which have the upstanding doubled-back flanges *j* that with the floor *g* form the bottom drawer guide.

The upper drawer guide is designated *k*.

and is shown in Figs. 2, 3 and 7. It comprises a sheet metal plate having stepped side flanges *l* and end flanges or hooks *m* at front and rear, the rear flange *m* fitting into the space between the plate *n* and rear wall *e* of the cabinet. The front flange *m* fits in the channel strip *o* (see Fig. 3). This channel strip *o* is fitted into the upper turned-over edge of the front plate *d* at this point 65 designated *p*, and the lower turned-over edge *q* of the plate *d* at this point, while the inside edge of the channel strip *o* is beaded over as at *r*. This anchors the drawer support *k*.

The cabinet drawers are designated *s* and comprise a single strip of metal forming side walls and the back wall and turned over into a finishing fold *t* at the top, and a locking fold *u* at the bottom that receives the 75 turned-over flanges *v* of the drawer floor *w*. These flanges *v* and locking fold *u* form runners for the drawer upon the steps *l* of the upper drawer support *k* and upon the floor *g* of the cabinet for the lower cabinet 80 drawers. The front of the strip *s* locks seams at *x* into the turned-back edge portion *y* of the front plate *z* of the drawer (see Fig. 4).

Now referring to Fig. 4 again, it will be 85 seen how the corners of the cabinets are formed and the various cabinet plates locked together. It will be seen that the side plates *b* and front plate *d* are provided with lock-seam folds *b*³ and *d*³. Corner strips *1* with 90 lock-seam folds *2* and *3* are adapted to slide into lock-seam relation with the folds *b*³ and *d*³ to securely lock the two walls *b* and *d* together at the corners. The same is done at all four corners of each cabinet. At the 95 drawer openings the front plate has turned-back folds *d*⁴ to reinforce the cabinet at this point in conjunction with the heavy metal strips *5* that are held by said folds as a reinforcement.

The legs are formed by continuations of the corner strips *1* in conjunction with a triangular fillet strip *6* (Fig. 9) having lock-seam folds *7* locking into the folds *2* and *3* of the corner strip. The caster spindle *8* is 105 provided with an anchoring collar *9* that serves to anchor the caster spindle frictionally in between the walls of the corner post. The caster wheel is designated *10*.

The two cabinets are secured together by 110 the center tie plate *11* (Fig. 2) that has lock-seam folds *12* at its side edges which

lock into the folds c^1 c^1 of the side walls c . This plate is shown in perspective in Fig. 10. This center plate 11 is provided with a front flange 13 with an opening to receive the drawer 14 (Fig. 5) and with a rear flange 15 turned over into a bead 16 adapted to receive the flange of the floor plate 17. The front and rear flanges 13 and 15 are provided with sub-flanges 19 and 20 that may be crowded in between the bead 2 of the corner strip 1 and the side wall c , as shown in the broken away portion in Fig. 2, to securely anchor the center tie plate to the two cabinets.

15 To further brace the two cabinets together, long bolts 21 run from one side wall c to the other side wall c of the two cabinets and are inclosed by a piece of sheet metal 22 which also acts as a spacer between the two cabinets.

20 To form the glass retainers, and also at the front and back of the desk to help join the two cabinets together, are four strips 23 of the construction shown in Fig. 8. 25 These strips lock into the turned-over upper folds b^1 , c^1 , d^1 and e^1 and can be slid into locking relation therewith. The ends are obliquely cut as at 24 (Fig. 8) to facilitate 30 sliding of the locking strips together. Each one of these strips 23 has an upstanding portion and turned-over bear 25 that acts 35 as a glass retainer.

40 A special feature of the construction described with the cabinets having turned-out 35 lock-seam folds and the locking strips 23 and tie plates, such as 11, is that any number may be coupled up into a single desk in much the same way that book sections may be put together to make a sectional book case of a number of sections.

45 It will be obvious that much of the construction claimed could be used on furniture in general, such as bureaus, chiffoniers, and any other pieces. We have, therefore, used 50 the word "desk" in the introductory phrase of the claims merely as words of description and not of limitation.

55 What we claim is:

1. In a metal desk, the combination of a 50 pair of drawer cabinets of sheet metal having inside walls provided at their tops with lock-seam folds, and a central tie plate provided at its sides with lock-seam folds adapted to lock in the said folds of the inner walls of the cabinets to tie the two cabinets together, said tie plate provided with front and rear flanges, the former provided with an opening, a floor supported on said front and rear flanges, and a drawer running 55 into the opening formed in the front flange.

60 2. In a metal desk, the combination of sheet metal cabinets provided with side walls having turned-over lock-seam folds at the top, said cabinets provided with corner joining strips, and a center tie plate having folds

65 at the sides that lock into the lock-seam folds of the cabinet and having front and rear flanges provided with sub-flanges adapted to lock in between the said corner strips and the side walls of the cabinets.

70

3. In a sheet metal desk, the combination of drawer cabinets provided at their front, back and outside top edges with turned-over lock-seam folds, and strips of sheet metal having turned-over lock-seam folds adapted 75 to slide endwise into locking engagement with the folds of the cabinet for readily assembling the cabinets together and to form a retainer for the top of the desk.

4. In a metal desk, the combination of a 80 pair of sheet metal cabinets having lock-seam folds turned-over at the top on each cabinet at front, rear and the outside, and sheet metal strips having on their under side a lock-seam fold adapted to engage 85 in the lock-seam folds of the cabinets for assembling the cabinets together and having an upright portion with a turned-over bead to act as a retainer for the top of the desk.

90

5. In a metal desk, a sheet metal cabinet comprising side walls including front and back walls, a sheet metal reinforcing plate n at the rear, a channel o secured to the front wall, and a drawer support and guide k having front and rear flanges m , m adapted 95 to lock into the plate n and the channel o .

96

6. In a metal desk, a sheet metal cabinet including four side walls secured together, 100 a drawer support and guide k supported by the front and rear side walls of the cabinet and provided with stepped side flanges l and a drawer s having runners formed by the lock-seaming of the side walls and bottom of the drawer, which runners engage 105 upon the steps of the side flanges to guide the drawer.

105

7. In a metal desk, a sheet metal cabinet comprising front, rear and side walls, the 110 side walls having turned-over folds at their bottoms, a floor having turned-down side flanges adapted to lock into the folds of the side walls, and guide plates i having turned-down flanges h engaging in the folds 115 of the turned-over lower edges of the side walls of the cabinet and having at their inner edges upright portions j which act as drawer guides.

115

8. In a sheet metal desk, the combination 120 of drawer cabinets provided at their front and rear with top edges turned over into lock-seam folds, and strips of sheet metal having turned-over lock-seam folds by which the drawer cabinets may be detachably assembled together and braced when the strips of sheet metal are slid into locking engagement with the lock-seam folds of the cabinet.

125

9. In a metal desk, a sheet metal cabinet 130

comprising side walls including front and back walls, a drawer-supporting guide supported by the walls and having step-like side flanges *l*, and a drawer provided with 5 depending runners supported to slide on said stepped side flanges.

10. In a sheet metal desk, the combination of drawer cabinets provided along one of the top edges with turned-out lock-seam 10 folds, and a strip of sheet metal having a turned-over lock-seam fold adapted to slide endwise into the folds of the cabinets for locking and assembling the cabinets together, substantially as described.

11. In a sheet metal desk, the combination 15 of a drawer cabinet provided at one edge with a turned-out lock-seam fold, and a strip of sheet metal having on its under side a lock-seam fold adapted to slide endwise into the lock-seam fold of the cabinet 20 and lock thereinto and having an upright portion adapted to act as a retainer for the top of the desk.

In testimony whereof we affix our signatures.

FRANK P. WILLIAMS.
ALLAN McINTYRE.
